CLAIM

The ornamental design for a towel box, as shown and described.

DESCRIPTION

FIG. 1 is a front, left and bottom perspective view of a box part of a towel box, showing my new design, shown separately for ease of disclosure;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a front and left perspective view of a bracket part of the towel box, shown separately for ease of disclosure;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is an exploded perspective view of two bracket parts of the towel box, shown in a state of use with a towel, and shown separately for ease of disclosure.

FIG. 16 is a perspective view of the towel box, shown fully assembled and in an open configuration;

FIG. 17 is another perspective view thereof;

FIG. 18 is a perspective view thereof, shown in a state of use with a towel;

FIG. 19 is an exploded view thereof;

FIG. 20 is a perspective view showing the towel box in a closed configuration; and,

FIG. 21 is a perspective view thereof, shown in a state of use with environment and the two parallel dashed lines in the figure represent the tearable segments of the towel.

(Continued)

The broken lines shown in the drawings depict environment and portions of the towel box, that form no part of the claimed design.
